(57) **CLAIM**

The ornamental design for a shielded cap assembly for drop tube rigid mount orbitor as shown and described.

DESCRIPTION

FIG. 1 is a top perspective view of a shielded cap assembly for a drop tube rigid mount orbitor according to the invention;

FIG. 2 is a side view thereof;

FIG. 3 is an opposite side view thereof;

FIG. 4 is a top view thereof;

FIG. 5 is a bottom view thereof;

FIG. 6 is a front view thereof;

FIG. 7 is a rear view thereof; and,

FIG. 8 is a bottom perspective view thereof.

The broken lines in the drawings show portions of the shielded cap assembly for drop tube rigid mount orbitor that form no part of the claimed design.
